JOHN A. JUMER, OF TWO HARBORS, MINNESOTA.

COLLAR FASTENER AND METHOD OF MANUFACTURING THE SAME.

Application filed January 16, 1924. Serial No. 686,678.

To all whom it may concern:

Be it known that JOHN A. JUMER, a citizen of the United States, residing at Two Harbors, in the county of Lake and State of Minnesota, have invented certain new and useful Improvements in Collar Fasteners and Methods of Manufacturing the Same, of which the following is a specification.

10 My invention relates to fasteners for garments and more particularly to fasteners for shirt collars and the like.

The main object of the invention is to furnish a fastener which grips the edges 15 of the button hole in a garment in such a manner that the fastener cannot shift either lengthwise or sidewise in the button hole but is also prevented from canting.

Another object of the invention is to provide an article of manufacture of this class 20 which can be produced from sheet metal at a very low cost by simply stamping out the fastener in one operation.

In the accompanying drawings one embodiment of the invention is illustrated and:

Figure 1 is an elevation of the fastener mounted in a shirt collar band;

Figure 2 is a perspective view of the fastener;

30 Figure 3 is a section along line 3—3 of Figure 1, in larger scale, and

Figure 4 is an elevation of the blank from which the fastener is made.

In the drawings, the reference numeral 35 10 represents the shield or body portion of the fastener or collar button which is substantially rectangular in outline and slit as at 11 upwardly from its bottom edge 12 and symmetrically on both sides of its center line 13. In this manner a tongue 14 is produced in the middle of the body portion, this tongue being solid or imperforate throughout and preferably slightly widened at its bottom edge.

45 Apertures 15 are stamped or cut out of the shield or body portion 10, which are also arranged symmetrically with relation to the center line 13. These apertures are spaced both from the edges of the body portion or shield 10 and from the tongue 14 so that side bars 16 are produced on the one hand and narrow strips running par-

allel with the side edges of the tongue 14 on the other hand. These narrow strips are cut across as at 17 so that an upstanding horn 18 is produced on each side of the tongue 14 at its free end.

The upper portions of the narrow strips formed by the cut 17 are bent upwardly on themselves constituting fingers 19 spaced 60 away from the body portion 10 slightly more than the thickness of the collar band 21 in order to accommodate the latter and grip the top edge 20 of the button hole.

Finally, the tongue 14 is bent outward 65 and again downward to provide a shoulder or bridge 22. The tongue 14 is thus spaced from the surface of the shield 10 about twice the distance between said surface and the fingers 19 so that both the collar band 70 and the collar can be gripped by the tongue.

As will be noted, there is scarcely any waste of material in producing this fastener and what is lost is only the small portions punched out of the plate to form apertures 75 15 which are principally provided as ornamentation.

In using the fastener, it is first inserted between the folds 23 and 24 that are generally provided at the back of the neck band. 80 The shield 10 is then permitted to remain between the two folds while the fingers 19 and the tongue 14 protrude through the button hole when the fingers will engage over the lower edge thereof. The button hole of the collar 25 is thereupon threaded on the tongue 14 which will thus hold the collar firmly in place.

It is evident that in some instances, when used for supporting other garments, the device would be applied in inverted position. In that case, a skirt, for instance, could be suspended from the hook shaped tongue 14.

Having thus described the invention, what is claimed as new is:

1. A method of producing an article of manufacture of the class described consisting in forming a substantially rectangular blank from sheet material, then cutting one edge of the blank to provide a bay with a central tongue and narrow fingers, and lastly bending the fingers and tongue in opposite directions and spacing them from the plane of the blank, 100

2. A fastener of the class described comprising a shield of substantially rectangular contour, a bay being formed in the shield and opening through one side thereof, a tongue projecting from the edge of the bay opposite the opening and pointing in the direction thereof, and fingers projecting from the same edge as the tongue

but in opposite direction thereof, the tongue and fingers forming integral parts ¹⁰ with the shield but being situated in a plane spaced from the shield.

In testimony whereof I affix my signature.

JOHN A. JUMER. [L.S.]
